UNITED STATES PATENT OFFICE.

WILLIAM D. LEWIS, OF PLYMOUTH, PENNSYLVANIA.

PICK-HEAD FASTENER.

Application filed July 2, 1923. Serial No. 649,147.

To all whom it may concern:

Be it known that I, WILLIAM D. LEWIS, a citizen of the United States, residing at Plymouth, in the county of Luzerne and State of Pennsylvania, have invented new and useful Improvements in Pick-Head Fasteners, of which the following is a specification.

The present invention relates to tools such as picks of the character in which a blade is detachably secured to the handle within a socket, and an object of the invention is to provide means which will securely and firmly lock a blade in its socket, against accidental displacement and which may be readily manipulated for releasing said blade.

The means employed to accomplish this object is the customary wedge, together with the specific formation of the blade and socket whereby the wedge has a sliding action within the stirrup or socket member attached to the handle. In instruments of this character the difficulty arises that the wedge so employed often becomes detached and lost, and an object of the invention is to provide means for preventing the disconnection of the wedge from walls of the socket.

Other objects of the invention are simplicity and durability of construction and cheapness of manufacture.

In the drawings accompanying and forming a part of specification—

Figure 1 is an elevation of a tool, showing the helve or handle in place within its housing and a blade such as a pick secured within a stirrup attached to the housing.

Figure 2 is a section on the line 2—2, Figure 1, showing the construction of the housing and of the eye within the stirrup, the handle or helve being omitted.

Figure 3 is a section on the line 3—3, Figure 2 showing still further the construction of the housing and the stirrup.

Figure 4 is a plan view of the wedge showing a slide member attached thereto and also indicating the method of closing the slot between the side members of said slide member.

Figure 5 is a section on line 5—5 of Figure 4 showing the sliding connection between the wedge and the helve housing.

Referring to the drawings in detail—

10 designates a handle or helve, 11 a pick blade preferably of steel and 12 a helve housing of any suitable material, preferably

of metal as cast-iron, formed to receive the helve or handle snugly therein, the housing being provided with apertures 13 through which fastening devices may be inserted if desired, for preventing the accidental displacement of the housing from the helve and preferably closed at one end by a wall 14 against which the inner end of the handle abuts when in place. Projecting from either side of the closed end of the housing are walls 15 connected at their outer ends by a wall 16, preferably thicker than the walls 15 for purposes of strength, and forming a stirrup having an eye or socket 18 therein. The helve housing 12 and the stirrup are preferably formed integral as shown, by casting or any other suitable method, although they may be formed separately and then brazed or otherwise secured together. Adjacent the wall 14, the walls 15 at the bottom of the eye are bowed outwardly to form grooves or slideways 17 for a purpose which will presently appear.

Located within the eye 18 of the stirrup is a wedge 19, preferably of malleable iron, having a longitudinal groove or channel 20 formed therein, which groove or channel is preferably closed at both ends, and secured to the wedge on the grooved side is a metallic slide plate 21 having a slot 22 formed longitudinally thereof and corresponding to the groove within the wedge, said slot however being of less width than said groove and lying centrally thereof. The base of the groove or channel 20 is parallel with and similarly inclined to that face of the wedge 19 which lies adjacent to the wall 14 of the helve housing, and the plate 21 bears flat against said face of said wedge with the slot 22 thereof extending longitudinally in central relation to the groove or channel 20. The wedge therefore consists of the two parts 19 and 21, but the two parts act as a whole. Secured to the end wall 14, preferably by riveting, is a lug 23 projecting through the slot 22 of the plate 21 and having a head 24 riding in the groove 20 of the wedge 19. The outer edges 25 of the plate 21 extend beyond the side edges of the wedge 19 and form flanges adapted to have a sliding fit in the slideways 17 described above. Moreover, it will be seen that the lug or headed stud 23 is secured to the wall 14 of the eye rather close to one end of the eye or socket 18 so as to permit a maximum movement of the

wedge 19 and its plate 21 and thus to make it possible to release the pick blade 11 or other tool member by moving the wedge and plate along the length of that side of the 5 blade which lies adjacent to the wall 14 so as to permit the outer wall 16 of the eye to be moved out of engagement with the recess 28 formed in the opposite side of the pick blade or other tool member 11. The 10 wedge 19 is preferably of such length that both ends thereof project beyond the housing 12. This construction adapts it to be readily loosened or tightened by a knock with a suitable instrument on the appropriate 15 ate end thereof.

From the foregoing, it will appear that the wedge while adapted to slide freely in the slideways, is at the same time limited in its sliding movement and prevented from 20 becoming disengaged from the eye of the stirrup and in order to hold the wedge in adjusted position when the blade 11 is in place, the upper surface of the plate 21 is roughened or formed with projections 26 25 which grip the head of the lug 23. Ready assembly of the wedge and stirrup is effected by constructing the plate 21 with one end of the slot 22 open and by providing the blank from which the plate is 30 formed with projecting portions 27 which, after the lug 23 has been inserted within the slot, may be peened over to close or partially close the opening.

The blade 11 is formed with a depression 35 28 adapted to snugly receive the thickened outer wall 16 of the stirrup which construction insures against accidental disengagement of the plate from its socket.

From the above description it will be seen 40 that I have provided a simple device adapted to connect a blade to a handle and to prevent the accidental disengagement of

said blade from its socket, and in which disengagement may be readily and simply accomplished by the operator, by simply 45 knocking on one end of the wedge. I have also provided against the wedge becoming accidentally lost or disengaged from the wall 14 by means of the sliding connection therebetween.

My invention has been shown in connection with a pick, but it will be understood that I do not wish to be limited to this specific construction, as the principles thereof are applicable to many and varied situations in which a blade or like member is to be attached within a socket.

Having described my invention what I claim is:

A device of the character described comprising a helve socket having an outer closed end and a stirrup projecting beyond said closed end, a wedge slidable through the stirrup and having a channel extending longitudinally thereof and formed with closed ends, the wedge including a plate secured thereto and formed with a longitudinal slot of less width than the channel and also provided with bendable projecting portions extending inwardly at opposite sides of the slot at one end, and a pin secured to said outer closed end of the socket adjacent one side edge of the latter and provided with a head of greater extent than the slot of the plate and freely movable in the channel of the wedge, the pin being inserted between the bendable projecting portions at one end of the opposite sides of the slot in the plate and said projections bent inwardly to close the slot and hold the pin in connection with the plate and wedge.

In testimony whereof I have hereunto set my hand.

WILLIAM D. LEWIS.
